MINING HEAD FOR CUTTING AND DISLODGING COAL

Frank Cartidge, Chicago, Ill., assignor to Goodman Manufacturing Company, Chicago, Ill., a corporation of Illinois

Application October 19, 1949, Serial No. 122,318

5 Claims. (Cl. 262—9)

This invention relates generally to continuous mining and specifically to an improved cutting, breaking and dislodging head for use with a continuous mining machine such as that disclosed in applicant's co-pending application on "Apparatus and System for the Continuous Cutting and Removing of Coal From the Solid," Serial No. 116,684, filed September 20, 1949.

One of the problems in continuous mining of coal, for instance, is that of removing the coal in sufficiently large particle sizes with a minimum of dust and fines. Accordingly, an object of the present invention is to provide a mining head which will produce coal in desirably large particle sizes with a minimum of power consumption.

An important feature of the mining head of the present invention is that it includes cutting means arranged to cut a plurality of spaced kerfs in a mining face to thereby define outstanding cores between the kerfs and breaker means aligned with the cores and spaced some distance behind the cutter means to break off the cores.

Ancillary features include the following: (A) the peripheral spacing of individual core breaking elements is greater than that of the individual kerf-cutting elements; and (B) the width of individual core breaking elements is substantially greater than that of individual kerf-cutting elements; both to facilitate maximum production size with minimum power consumption.

Other objects and advantages will be apparent from the following description taken in connection with the drawing in which:

Figure 1 is a top plan view, partly in section, of a cutting, breaking and dislodging head according to the present invention;

Figure 2 is a sectional view of Figure 1 taken along the line 2—2 of Figure 1;

Figure 3 is a perspective view of one of the core breaking elements; and

Figure 4 is a perspective view of one of the kerf-cutting elements.

Like parts are designated by like reference characters throughout the figures of the drawing.

To simplify the disclosures herein to their fundamentals, only the novel mining head itself is shown and described. It will be understood, however, that in use it could be substituted for the cutting and dislodging element generally designated 15 in the above-mentioned co-pending application. For a detailed description of the entire mining machine and its operation, reference therefore should be made to the previous application.

The novel head herein generally designated 11 comprises supporting means 12 which latter includes both a pair of cutter bars 165 and a drum 169. Carried by the supporting means 12 are rows of cutting means generally designated A and which are arranged to cut a plurality (in this case 4) of rows of kerfs 13 in a working face 14. Arranged intermediate the kerf-cutting means are core breaking means generally designated B aligned with cores 16, 16 defined by the kerfs and adapted to break up and dislodge the cores after they have been defined by the cutting of the kerfs.

The cutter bars 165 are mounted for pivotal movement about both horizontal and vertical axes and may be fed toward and retracted from the working face (by means shown in the above-mentioned co-pending application).

A cutter chain 17 having kerf-cutting bits 18 project-

2

ing therefrom is guided for orbital movement about each cutter bar 165 in a well known manner.

The drum 169 is rotatably mounted between the forward ends of the cutter bars 165 by means now to be described. A main tubular section 19 has at each end an inner telescopically assembled section 21 welded thereto after assembly of a mounting shaft 22 therewithin. The latter is held at each end within a collar 23 carried by one of the cutter bars and is held fast by means of a lock nut 24 and washer 26. A pressure ring 27 is urged inwardly by the lock nut and washer to maintain the bearing 28 seated firmly within a seat 29 formed in the section 21. A sprocket 31 driven by chain 17 is carried by each section 21 and is keyed against relative rotation as at 32. An outer grease retainer 33 for the bearing is carried on the sprocket by means of screws 34, an inner grease retainer being provided at 36.

Arcuate shoes 37 arranged in pairs, each extending half-way around, are mounted on the periphery of drum 169 as by welding at 38. Each pair of shoes has a plurality (in this case 8) of cutter blocks 39, each with a kerf cutter bit 41 carried therein. Each cutter bit is removably mounted by means of a lock screw 42. It will be noted that the individual kerf-cutting bits 18 and 41 are preferably single-pointed tools disposed in different directions to cut the relatively wide kerfs 13 at maximum speed.

An important feature of the present invention resides in the rows of core breaker means B. This comprises a plurality (in this case 3) of circumferentially extending rows of individual core breaker parts 43 mounted about the periphery intermediate the rows of kerf-cutting means A. Two bits are carried in opposite end portions of arcuate shoes which themselves are welded in pairs onto the periphery with the bits spaced at regular intervals about the drum. The bits are removably held in place by lock screws 44 in the same manner as bits 18 and 41.

As best shown in Figure 3, the individual core breaker bits 43 are constructed to scrape and break off the cores in relatively large pieces. By contrast to the single-point cutting bits 41, the breaker bits 43 are preferably constructed with considerable width so as to engage the core at at least two points spaced transversely of the direction of movement. To this end the bits 43 are constructed with transversely spaced points 46, 46 with a shallow relief 47 therebetween. In operation, the core will be cracked out along the lines a shown in Figure 1. Any central portions of the cores not falling off immediately upon cracking will be scraped off by the bits on a subsequent pass.

The kerf-cutting bits 41 are primarily designed for cutting speed rather than for large particle size; hence, the single-pointed construction in the particular arrangement shown. Thus, for maximum speed of kerf-cutting combined with maximum particle size produced from the cores, the core breaker bits will not only be wider than the kerf cutter bits but they will be spaced at greater intervals about the periphery. In connection with this latter point, it will be seen that the kerf cutter bits 41 are spaced at approximately 45° intervals about the drum while the other kerf cutter bits 18 are spaced even closer; as contrasted with the core breaker bits spaced at approximately 90° intervals.

Another important feature of the invention is that the cutter bits 18—41 extend farther than the breaker bits 43 beyond the support means 12 in order that the kerfs 13 be cut to define the outstanding cores 16 before the corresponding portions of the latter are engaged and broken off by the core breakers.

In operation the head 11 will be elevated to the top of a seam of coal, for example, and while being rotatably driven (clockwise, Figure 2) will be swung downwardly at successive forward positions. Gathering arms and conveyor means (see co-pending application) will be utilized to carry the coal away from the face. It will be observed that during this operation the kerf cutters 18—41 always operate in advance of the breakers 43, which latter break up and discharge the cores by direct frontal attack.

While a preferred form of the invention has been illus-

trated and described, it will be obvious that details of construction and arrangement of parts may be variously changed and modified without departing from the spirit and scope of the invention.

I claim as my invention:

1. In a continuous rotatable cutting, breaking and dislodging head adapted to cut, dislodge and break down coal and the like from a solid face by bodily movement horizontally into the face adjacent one vertical extremity thereof and vertical movement therealong to a position adjacent the other extremity thereof during continuous rotation of said head, a rotatably driven drum, a plurality of relatively closely circumferentially spaced kerf-cutting bits projecting from the periphery of said drum in laterally spaced concentric rows and extending at various angles with respect thereto, and a row of core breaker bits disposed between at least two rows of said kerf cutter bits, said core-breaker bits extending radially from the periphery of said drum and having a greater spacing than the spacing of said kerf-cutting bits and having relatively wide advance breaking and scraping faces and terminating at a lesser distance from the axis of rotation of said drum than said kerf-cutting bits, to travel at a lesser linear velocity than the linear velocity of said kerf-cutting bits, and intermittently engage the core face and break up the core between said kerf-cutting bits into lumps of relatively large particle sizes.

2. In a continuous rotatable cutting, breaking and dislodging head adapted to cut, dislodge and break down coal and the like from the solid by bodily movement horizontally into a coal face adjacent one extremity thereof and vertical movement therealong to the other extremity thereof and withdrawal therefrom, spaced apart support means for said drum comprising two spaced apart vertically and horizontally movable vertically extending cutter bars having cutter bit-carrying cutter chains guided for orbital movement thereabout, a drum rotatably supported between said cutter bars, adjacent the forward end thereof and rotatably driven by said cutter chains, a plurality of kerf-cutting bits relatively closely spaced circumferentially projecting from the periphery of said drum in laterally spaced concentric rows and extending at various angles with respect thereto and having cutting points spaced closely together to have substantially continuous engagement with the face of the coal for cutting a plurality of laterally spaced vertical kerfs therein, and a row of core breaker bits disposed between each two rows of kerf-cutting bits, said core breaker bits being spaced apart a greater distance than said kerf-cutting bits and subscribing circles of substantially less diameter than the circles subscribed by said kerf-cutting bits and having widely spaced cutter points with a relief therebetween to form advance breaking and scraping surfaces intermittently engaging the faces of the cores between the kerfs cut by said kerf-cutting bits and breaking and scraping the cores from the coal face in relatively large particle sizes.

3. In a continuous rotatable cutting, breaking and dislodging head adapted to cut, dislodge and break down coal and the like from the solid by bodily movement horizontally into the coal face adjacent one extremity thereof and vertical movement therealong to the other extremity thereof during rotation thereof, a rotatably driven drum rotatable about a horizontal axis extending parallel to the working face during the dislodging operation, means for supporting and rotatably driving said drum including two laterally spaced cutter bars having orbitally driven cutter bit carrying cutter chains movable thereabout, sprockets on said drum meshing with and driven by said cutter chains for changing the direction thereof and rotatably driving said drum, a plurality of concentric rows of cutter bit blocks extending from said drum in laterally spaced relation with respect thereto and extending at various angles with respect thereto in relatively closely spaced circumferential relation with respect to each other and

75 having cutter bits detachably carried thereby and presenting substantially continuous kerf-cutting points, cutting in substantially the same planes as the bits of said cutter chains, and a row of widely spaced blocks disposed between each two rows of kerf cutter bits and having core breaker bits carried thereby, said core breaker bits sub-scribing circles of substantially less radius than the circles subscribed said kerf cutter bits and having relatively widely spaced advance breaking and scraping faces, for intermittent engagement with the faces of the cores between the kerfs cut by said kerf cutter bits, breaking and scraping the cores from the coal face in relatively large particle sizes by direct engagement with the core faces.

4. A cutting, breaking and dislodging head for a continuous mining machine comprising a rotatable drum adapted to be moved forwardly and backwardly relative to a mine working face and vertically therealong from one extremity to the other and rotatably driven about an axis substantially parallel to the working face, said drum having mounted on the periphery thereof at least two axially spaced rows of kerf-cutting bits relatively closely spaced circumferentially and forming substantially continuous cutting members, and at least one row of core breaker bits therebetween, the kerf-cutting bits extending a greater distance radially from the axis of rotation of said drum than said core breaker bits whereby the former will first cut spaced kerfs to define an outstanding core therebetween, and said core breaker bits having widely spaced cutter points with a relief therebetween whereby said core breaker bits will intermittently engage the face of the core between the kerfs cut by said kerf-cutting bits and break up and dislodge said core from the coal face in relatively large particle sizes, said core breaker bits being spaced at greater intervals than the kerf-cutting bits about the circumference of the drum to break up and scrape off the cores in relatively large particle sizes.

5. A cutting, breaking and dislodging head for a continuous mining machine comprising a rotatable drum adapted to be moved forwardly and backwardly relative to a mine working face and vertically therealong from one extremity to the other and rotatably driven about an axis substantially parallel to the working face, said drum having mounted on the periphery thereof at least two axially spaced rows of kerf-cutting bits circumferentially spaced substantially 45° apart and forming substantially continuous cutting members and also having at least one row of core breaker bits between said rows of kerf-cutting bits and having two axially spaced cutter points with a relief therebetween, said core breaker bits being spaced apart at least 90°, said kerf-cutting bits extending a greater distance radially from the axis of rotation of said drum than said core breaker bits whereby said kerf-cutting bits will first cut spaced kerfs to define an outstanding core therebetween following which said core breaker bits will intermittently engage the face of the core and break up and dislodge said core from the coal face in relatively large particle sizes by direct cutting and scraping engagement with the face thereof.
